UNITED STATES PATENT OFFICE.

VICTOR WILLOUGHBY, OF JEFFERSONVILLE, INDIANA, ASSIGNOR TO AMERICAN CAR AND FOUNDRY COMPANY, OF ST. LOUIS, MISSOURI, A CORPORATION OF NEW JERSEY.

MAIL-POUCH RACK.

1,224,823.

Specification of Letters Patent.

Patented May 1, 1917.

Application filed September 2, 1914. Serial No. 859,885.

To all whom it may concern:

Be it known that I, VICTOR WILLOUGHBY, residing at Jeffersonville, Clark county, Indiana, and being a citizen of the United States, have invented certain new and useful Improvements in Mail-Pouch Racks, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings:

Figure 1 is a plan view of my improved mail pouch rack.

Fig. 2 is an end elevation thereof.

Figs. 3, 4 and 5 are plan, front elevational and side elevational views, respectively, of one of the double hooks.

Figs. 6, 7 and 8 are similar views of one of the single hooks; and

Fig. 9 is a substantially horizontal sectional view, diagrammatically illustrating the support of a pouch.

To properly accumulate into orderly groups a confused mass of intermingled elements of variously designated lots, as, for example, the sets of mail matter received in disordered state by a postal, or other system, and addressed to different localities, is so difficult and important a task that mechanical contrivances are indispensable aids.

My present invention constitutes such an aid, relates to mail pouch racks, and has for an object the provision of a rack of the class referred to which shall be in constant condition for service without manipulation or adjustment of its parts.

Another object is to combine with a simple frame, constructed of inexpensive commercial materials, a requisite number of pouch-holding devices of such similar, rugged and easily produced design, that the rack as a whole will be too incomplex to be subject to disarrangement, breakage, or the cost of devices of this class which are constructed of a greater number of parts, or which require more expensive manufacturing.

It is also purposed to so arrange the pouch-holding devices that pouches suspended therefrom will, upon the simple action of attaching them, adjust their openings to give maximum ingress to their interiors.

Other advantages which may appear hereinafter are obviously a part of the present conception and are to be understood as coming within the scope of the invention herein disclosed.

In the drawings, 1 indicates a top frame or rack, inclined upwardly as it proceeds toward the rear and comprises spaced parallel supporting members, or tubes, 2, 3 and 4, and connecting end members. Each end member preferably comprehends segmental tubes 5 united by a fitting, as the pipe-T 6, which joins said end member to the central supporting tube or member 3, and side outlet elbows 7 at the outer ends of the tubes 5, joining the end member to the front and rear supporting members, 4 and 2, respectively, the side outlet of each elbow 7 being directed downwardly.

Connected at their upper ends to said depending side outlets of elbows 7 are corner posts or tubes 8, to the lower portions or extremities of which are secured fourway T-fittings 9, a tubular or other shaped bottom end tie member 10 joining the fittings 9 of the front and rear upright tubes 8 at each end of the structure as a whole.

Running longitudinally are front and rear bottom tie members, shown at 11 and 12 in Fig. 2, which connect respectively, the front corner posts and the rear corner posts.

A boxlike skeleton structure is thus produced, comprising the top frame or inclined rack 1, a front frame, a back frame, a pair of end frames and a bottom frame, resulting in a strong, rigid and unyielding construction, which may be suitably raised from the floor by plugs 13, or other devices, as casters, secured to the bottoms of fittings 9.

The top frame or rack 1 has already been described and the front frame comprehends front supporting member 4 of rack 1, forward elbows 7 thereof, front corner posts 8, forward four-way T-fittings 9 and front bottom tie member 11.

The back frame is similar to the front frame, the rear supporting member 2 of rack 1, rear elbows 7, rear cover posts 8, rear

four-way T-fittings 9 and the rear bottom tie member 12, duplicating the corresponding parts of said front frame.

The end frames are also alike, and each 5 comprises one of the end connecting members which has its tubes 5 united by T-fittings 6, a front and rear elbow 7, a front and rear corner post 8, the four-way T-fittings carried by each of the latter and the 10 end bottom tie member 10 connecting said fittings. The bottom frame comprises the front and rear bottom tie members, both bottom end tie members, and the four-way T-fittings 9 which connect all of the bottom tie 15 members together.

Mounted upon each of the front and rear supporting members, 4 and 2, respectively, of rack 1, are pluralities of single pouch hook devices 13, and carried in a like manner by the central supporting member 3 are 20 double pouch hook devices 14, equal in number to the single hook devices carried by each of the other supporting members, and adapted to coöperate with said single hook 25 devices carried by both the front and rear supporting members, 4 and 2.

Each single and double pouch hook device, 13 and 14, is provided with an attachment portion 15, here illustrated as a tube-embracing member. Positioned to extend to one side and below the attachment portion 30 15 of each single hook device 13, is a horizontally disposed L-shaped pouch-sustaining hook 16 of angular cross section, 35 connected to the attachment portion 15 of the same hook device 13, preferably by an integral hanger 17, shown in the drawings to be horizontally disposed and to merge both with the attachment portion 15 and the vertical flange of that part of the L-shaped hook 16 which parallels said attachment portion.

Double hook devices 14 have the same construction as the single hook devices 13, except that each is supplied with a pair of oppositely extending L-shaped pouch-sustaining hooks 16^a, instead of the single hook 45 16 of devices 13, and all of the corresponding parts except the hooks have been designated by the same reference numerals.

Both the single and double hook devices 13 and 14 are arranged transversely of rack 1 in alined rows, and longitudinally of their respective supporting members, 2, 3 and 4, 55 in relatively widely spaced associated pairs, said pairs being closely positioned to each other to conserve the space included within the area of the rack 1.

Hooks 16 and 16^a, of hook devices 13 and 60 14, each have a portion paralleling the axis of their attachment portions 15, and another outwardly extending portion continuing beyond a bend at substantially right angles to the first mentioned portion. When said hook devices are positioned in the rack 1 as

described, the outwardly extending portions of hooks 16^a project toward the corresponding portions of hooks 16 of the single hook devices 13, which are transversely alined with said double hook devices 14.

Said axis-parallel portions of each associated pair of the hooks 16, which are carried by the same supporting member 2 or 4, project toward each other, as do the corresponding portions of hooks 16^a of associated pairs.

In consequence of these conditions, rack 1 contains a series of grouped pouch-sustaining hooks 16 and 16^a, each set forming the corner angles of an imaginary rectangle, thus creating an intermittent circuitous frame, and being adapted to sustain a pouch. Suitably mounted, as upon supporting members 2 and 3, are label holders 18 for holding destination-indicating labels for 80 the various hook sets adapted to support pouches.

To suspend a pouch from any of the sets of hook devices, its opening is first distended, and points in the edge thereof are 90 hooked over the horizontal flanges of, say, an associated pair of hooks 16^a located on the same side of the central supporting member 3, as diagrammatically indicated in Fig. 9, where the pouch is indicated by A. 95 With a portion of the edge of said opening extending to inclose, bear against and conform to the vertical flanges of the associated pair of hooks 16^a, and lapping and resting upon the horizontal flanges thereof, the 100 front side or edge of the opening of the pouch is drawn forwardly and upwardly and caused to lap and rest upon the horizontal flanges of associated hooks 16 of the affiliated single hook devices 13.

In some instances, the pouch opening may be stretched so that it will naturally contract after such stretching, and assume a relation to hooks 16 and 16^a approximately that shown in Fig. 9, but for greater reliance, the draw-string B may be pulled to cause the perimeter of the pouch opening to closely engage the vertical flanges of said hooks 16 and 16^a, and the ends of said draw-string may be fastened, as by a slip-knot, to 110 insure the maintenance of the relationship of the pouch opening and said hooks.

The removal of the pouch involves only a loosening of the pouch opening and a slight manual freeing action upon the part 115 of the attendant.

Obviously, the rack may have other forms and capacities than that shown, best suited to the needs of any particular installation.

What I claim is:—

In a device of the class described, a central supporting member and additional supporting members spaced therefrom on opposite sides thereof, and longitudinally spaced pairs of constituent pouch-holding 125

devices carried by each supporting member, aligned transversely of said members and grouped into sets each adapted to hold a pouch with its opening expanded each 5 pouch-holding device having a means for girdling one of said supporting members, those devices carried by the outer supporting members being each provided with a single inwardly extending L-shaped hook of 10 angular cross section and means connecting the same with the girdling means of said device, and those devices carried by the cen-

tral supporting member each being provided with a pair of oppositely extending L-shaped hooks of angular cross section and 15 means for connecting the pair of hooks to the girdling means of said device.

In witness whereof I have hereunto set my hand in the presence of two witnesses.

VICTOR WILLOUGHBY.
